(57) **CLAIM**

The ornamental design for a lifting table, as shown and described.

DESCRIPTION

FIG. 1 is a front and top perspective view of a lifting table showing our new design.

FIG. 2 is a rear and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is an enlarged view of an encircled portion of the lifting table labeled 9 shown in FIG. 3.

FIG. 10 is an enlarged view of an encircled portion of the lifting table labeled 10 shown in FIG. 3; and,

FIG. 11 is an enlarged view of an encircled portion of the lifting table labeled 11 shown in FIG. 8.

The broken lines in the drawings depict portions of the lifting table that form no part of the claimed design, and the circular broken lines depict the boundary of the enlarged views and form no part of the claimed design.

1 Claim, 11 Drawing Sheets
